UNITED STATES PATENT OFFICE.

LILLIAN M. SAYEN, OF ROCK, MICHIGAN

BED-COMMODE.

1,054,452.

Specification of Letters Patent.

Patented Feb. 25, 1913.

Application filed May 16, 1912. Serial No. 697,636.

To all whom it may concern:

Be it known that I, LILLIAN M. SAYEN, a citizen of the United States, residing at Rock post-office, in the county of Delta and 5 State of Michigan, have invented certain new and useful Improvements in Bed-Commodes, of which the following is a specification.

One of the objects of my invention is to 10 provide a commode for invalids that can be used without disturbing the patient when in an incubent position.

My device is especially adapted for use 15 in obstetrical cases, or in cases where cytognistic treatment is to be administered to a bed ridden patient. Its ease of manipulation; cleanliness resulting from its use and the comfort and the indifference of the patient while it is being used are features 20 that contribute to make it a valuable and appreciable addition to a sick chamber, or hospital.

Other and further objects of my invention will readily become apparent to those 25 persons who are skilled in the art, from a consideration of the description taken in conjunction with the drawing wherein:

Figure 1 is a perspective view of a mattress having a central perforation adapted 30 for use with my commode attachment; Fig. 2 is a similar view of a closure for the mattress perforation, or opening. Fig. 3 is a longitudinal central section, through the mattress and the spring bed support showing the bed pan of my commode in position; Fig. 4 is a broken away portion of the spring, mattress-support, showing a plan view of that portion thereof that is located immediately below the perforation 35 in the mattress. Fig. 5 is the commode pan, or vessel, adapted to hold the fluids and other matter that may pass through the perforations in the mattress, and spring support. Fig. 6 is a transverse section taken 40 on line 6—6, of Fig. 4.

In all the views the same reference characters indicate similar parts.

The mattress 10 is provided with a perforation 11, lined with a waterproof fabric 12. 50 When the mattress is in place, superposed upon the bottom 13, which may be of any desirable construction, and it is immediately above a similar perforation 14, made in the square plate 15. The perforation 14, in the

plate 15, may for convenience, be made somewhat larger than the perforation 11, in the mattress 12; and said plate may be supported, by the frame 18, in any convenience manner. As shown, in this case, perforations are made in the edges of the plate in which the wires 16 are secured. Cleats 17 and 18, are secured to the underside of the plate 15, as shown in dotted lines in Fig. 4. These cleats are intended for support of the pan, or vessel 19, the side wings 20 and 21 whereof overlie the in-turned edges of the cleats 17 and 18, as shown in Fig. 3. The vessel 19 is provided with a handle 22, by means of which it may be inserted in position with reference to the cleats and the perforation 14. A transversely positioned bar 23, is pivoted to the plate 15, as at 24, and is adapted to engage a supporting latch 25, on the opposite side of the perforation 14, and the plate 15. The bar 23, is intended to support the closure 26, for the perforation 11 in the mattress 10. The closure 26 is made of substantially the same material of which the mattress is composed, so that when it is in place, to fill the perforation 11, it is uniformly yielding with the mattress. The closure 26 will pass completely through the opening or perforation 11, in the mattress and it is held in its position by means of the bar 23.

When the device is to be used, the bar 23 is moved on its pivot 24, so that it occupies a position substantially parallel with the cleat 17, as shown in Fig. 3, at which time the closure 26 may be removed from the bottom of the mattress and through the perforation 14 of the spring support structure 13. When the device is being prepared for use, the pan, or vessel 19, is placed by sliding it transversely with respect to the mattress, on the cleat support 17 and 18, by engagement of the flanges 20 and 21 with the cleats, about the same time and before insertion of the pan, the bar 23 is turned on its pivot 24 until it is substantially parallel with the cleat 17 at which time the closure 26 may be removed from the opening from the bottom of the mattress without disturbing the patient. After the commode has been used the pan may then be removed from its position and the bar 23 returned to the position shown in Fig. 4, after the clo-

sure 26 has first been placed in the opening in the mattress 11, the bar 23 then supports the closure 26, in place. By this operation it will be observed that the patient need not be moved or disturbed.

For purpose of cleanliness the pan 19 may be lined with porcelain like, or other vitreous material and the plate 15 may be likewise treated, so that the surfaces of the parts may be quickly and easily cleansed.

One of the special advantages of my construction is due to the fact that the operations necessary and incident to its use may all be performed below the mattress structure without disturbing the patient, or causing the patient any inconvenience or discomfort.

While I have herein described, for the purpose of complete disclosure, a specific embodiment of my invention I desire to be understood that I do not consider my invention to be limited to the specific construction shown further than defined by the appended claims.

Having described my invention what I claim as new and desire to secure by Letters Patent is:

1. In a supporting structure for a mattress having a perforation and closure, the combination of a plate having a perforation larger in diameter than the closure to be used therewith, means upon the under side of said plate to support a pan under said perforation slidably removable therefrom, a closure-retaining bar pivoted to the plate at a point near the edge of the perforation for movement in a horizontal plane from closure-retaining position to a position out of the path of movement of a mattress closure vertically through said perforation, and means on the side of the perforation which is diametrically opposite to said pivot point of the bar to engage the free end of said

horizontally pivoted bar for prevention of such removal of a mattress closure.

2. In a supporting structure for a mattress having a perforation and a closure therefor, the combination of a plate having a perforation for passage therethrough of a mattress closure to be used therewith, longitudinal members secured to and extending from opposite edges of said plate, transversely arranged cleats on the under side of said plate, a pan having wings whereby said pan is slidably insertible in said cleats to be moved to a position beneath said perforation in the plate, a bar pivoted on said plate between said cleats for movement in a horizontal plane from a position parallel to said cleats to a position diagonal with respect to the plate, respectively to permit removal of a mattress closure in a straight vertical path through said perforation in the plate and to retain said closure in said perforation in the mattress.

3. In a supporting structure for a mattress having a perforation and a closure therefor, the combination of a plate having a perforation, a movable member carried on the under side of said plate adapted for movement to either of two positions respectively in or out of the vertical path of movement of a mattress closure through said perforation in the plate, and pan-supporting means carried on the under side of said plate and operable, with said movable member in either of said two positions, to support a pan under said perforations in the plate.

In testimony whereof I hereunto set my hand in the presence of two witnesses.

LILLIAN M. SAYEN.
